UNITED STATES PATENT OFFICE.

ISAAC W. PRICE, OF McCONNELLSVILLE, OHIO, ASSIGNOR OF ONE-HALF TO
ELLIS A. GREGG, OF TRIADELPHIA, OHIO.

SWAGING-TOOL.

SPECIFICATION forming part of Letters Patent No. 634,909, dated October 17, 1899.

Application filed February 21, 1899. Serial No. 706,427. (No model.)

To all whom it may concern:

Be it known that I, ISAAC W. PRICE, a citizen of the United States, residing at McConnelsville, in the county of Morgan and State 5 of Ohio, have invented a new and useful Improvement in Swaging-Tools, of which the following is a specification.

My invention relates to swaging-tools, and has for its object to provide a tool by the use 10 of which one man can do the work usually done by two. This object I accomplish in the manner and by the means hereinafter more fully described in detail, and particularly pointed out in the claims, reference being had to the accompanying drawings, in which like reference-letters indicate like parts in all the figures.

Figure 1 is a side elevation of my invention. Fig. 2 is a top plan view of lower part 20 of same. Fig. 3 is a sectional view on line *x x*, Fig. 1. Fig. 4 is a sectional view on line *y y*, Fig. 1.

My invention consists of a swaging-tool formed of two parts. The bed-piece A, which 25 rests on the anvil when in use, has a projection *a*, adapted to enter a complementary recess in the anvil, and is provided at one end with two arms *a'*, having a small space between them and curving upward. The ends 30 of these arms *a'* have holes *a²*. The upper part B of the swaging-tool has a projection *b*, rising from the center of its top, adapted to receive the blows of the hammer, and an arm *b'*, which extends out from one end and is 35 adapted to fit between the ends of the arms *a'*. The arm *b'* is pierced by an oblong transverse slot *b²*, which registers with the holes *a²*. A pin C fits in the holes *a²* and passes loosely 40 through the slot *b²*, connecting the parts A and B pivotally, so that the upper part B may be raised a short distance, and allowing a certain freedom of play to the upper part B. The outer end of the arm B is tapered off and curved upward. The upper surface of the 45 bed-piece A has transverse grooves *a³* of any desired shape, and the upper part B has on its lower surface complementary grooves *b³*.

The operation of my invention is as follows: The bed-piece A is placed on the anvil, the 50 projection *a* in its complementary recess, and

a tap on the outer end of the arm *b'* given with the hammer. This causes the upper part B to rise until the arm *b'* binds against the inner side of the ends of the arms *a'*, when it stops and remains suspended. The operator now places the heated metal in the groove on the bed-piece A and taps the projection *b*. This causes the upper part B to fall on the bed-piece A, and the metal is now between the two parts A and B in the grooves *a³ b³*. 60 The operator now strikes the projection *b* until the metal is swaged as desired or becomes cold, when a tap on the outer end of the arm *b'* raises the upper part and releases the metal. Owing to the form of the slot *b²* the operator 65 can cause the upper part B to rock sidewise and give a tapering swage to the metal.

Having thus described my invention, what I claim as new, and desire to secure by Letters Patent, is—

1. A swaging-tool consisting of two parts, a bed-piece having a transverse groove in its upper surface, said bed-piece at one end provided with two arms extending in a curve outward and upward, and a part having complementary grooves in its under surface said part provided at one end with an arm extending outward and pivotally secured between the ends of said first-mentioned two arms, the outer end of said arm tapered and curved upward, substantially as shown and described. 70

2. A swaging-tool consisting of two parts, a bed-piece having a transverse groove in its upper surface and a square downward projection from its under surface, said bed-piece 75 provided at one end with two arms extending in a curve outward and upward, and a part having complementary grooves in its under surface, and a projection rising from its upper surface, said part provided at one end with an arm extending outward and pivotally secured between the ends of said first-mentioned two arms, the outer end of said arm tapered and curved upward, substantially as shown and described. 80

3. A swaging-tool consisting of two parts, a bed-piece having a transverse groove in its upper surface and a square downward projection from its under surface, said bed-piece provided at one end with two arms extending 90

95

100

in a curve outward and upward, and a part having complementary grooves in its under surface, and a projection rising from its upper surface, said part provided at one end 5 with an arm extending outward and pivotally secured between the ends of said first-mentioned two arms, by a pivot passing loosely through said arm, the outward end of said

arm tapered and curved upward, substantially as shown and described.

In testimony whereof I hereto affix my signature in the presence of two witnesses.

I. W. PRICE.
